(21) Appl. No.: **29/372,430**

CLAIM

(22) Filed: **Nov. 18, 2010**

The ornamental design for an “liquid dispensing apparatus for use in preparing flavored beverages,” as shown and described.

(30) **Foreign Application Priority Data**

May 18, 2010 (DE) 40 2010 002 757

DESCRIPTION

(51) **LOC (9) Cl.** **07-01**

FIG. 1 is a right front perspective view of a liquid dispensing apparatus for use in preparing flavored beverages showing our new design;

(52) **U.S. Cl.** **D7/306**; D7/311; D7/309

FIG. 2 is a right front perspective view thereof with the environmental structure removed;

(58) **Field of Classification Search** D7/300,

FIG. 3 is a front view thereof;

D7/305, 306, 313, 316, 317, 309, 311; 222/185.1,
222/146.6, 183; 210/774; D15/82; D23/207

FIG. 4 is a right side view thereof, the left side view being a
mirror image thereof;

See application file for complete search history.

FIG. 5 is a top view thereof;

(56) **References Cited**

FIG. 6 is a rear view thereof;

U.S. PATENT DOCUMENTS

FIG. 7 is a left side view thereof in open position;
